UNITED STATES PATENT OFFICE

GEORGE M. PELTON, OF MILWAUKEE, WISCONSIN, ASSIGNOR TO THE FILER & STOWELL CO., OF MILWAUKEE, WISCONSIN, A CORPORATION OF WISCONSIN

DOGGING MECHANISM

Application filed October 20, 1928. Serial No. 313,820.

This invention relates to dogging mechanism for use in connection with the knees of a saw mill carriage and particularly to specific improvements in that type of such mechanism wherein the dogs may be adjusted relative to the face of the knee and such dogs are adapted for successive operative movement through the same power means.

This application is filed as a continuation in part of my application filed May 19, 1927, Serial No. 192,723, for saw mill dogging means.

Mechanism of this type is in actual practice necessarily of a more or less cumbersome nature to withstand the strains of the work in hand and such mechanism has been heretofore mounted on but wholly at one side of the knee, with a consequent tendency to unbalance the knee to some extent, and further involving the projection of the added parts beyond the side of the knee with the almost certain liability of providing an undesirable obstruction, and at best presenting a comparatively crude and unsightly appearance.

A characteristic and important feature of the present invention is the disposition of the dogs; and the direct means for positioning the dogs relative to the face of the knee and for operating the dogs in their engagement with the log, is arranged wholly within the normal outline of the knee, that is, between what may be termed the side walls thereof and substantially centrally of the knee to thereby eliminate the overbalancing tendency of such parts; and to place such parts in the most effective positions in connection with dogging a log and avoid the projection of such parts beyond the side of the knee.

A further object of the invention is the provision of fluid pressure means for operating the dogs to and from dogging relation wherein, through the use of differential pressure surfaces, the loss of pressure medium is restricted to a minimum and the control of such pressure medium is materially simplified.

A further object of the present invention is the provision of means for adjusting the dogs in their projection beyond the face of the knee through a fluid pressure means involv-

ing differential pistons controlled through such differential pressure surfaces, with a minimum loss of motive fluid and a material simplification of the control of such fluid.

A further object of the invention is the particular construction of the crank connection through which the dog carrying bar is adjusted in order that excessive wear and lost motion in the parts may be reduced to a minimum.

A further object of the invention is to simplify the construction and arrangement of certain necessary parts of the apparatus in order to avoid complication in construction and operation, and permit the use of heavier appropriate wear and strain resisting material which, if arranged entirely beyond the knee, would be objectionable through its overbalancing influence and its obstructive arrangement.

The invention is illustrated in the accompanying drawings, in which:

Figure 1 is a view in vertical section through the knee, partly broken away, the upper dogs being shown at their downward limit, and both upper dogs at their inner position relative to the face of the knee.

Figure 2 is a front view of the same.

Figure 3 is a section on line 3—3 of Figure 1.

Figure 4 is a perspective view showing the dog supporting brackets and the guide bar on which they are mounted.

Figure 5 is a section on line 5—5 of Figure 2.

Figure 6 is a broken perspective showing the relation of the knee and rack bar, and illustrating particularly the opening in the knee bottom to receive the lower dog.

Figure 7 is a broken perspective of the rack bar showing the latter recessed to permit the necessary movement of the lower dog.

Figure 8 is a detail in elevation showing a modified mounting for the lower dog, designed particularly for use in connection with rack and pinion mechanism for the knee.

Figure 9 is a broken elevation illustrating a further type of movable lower dog.

Figure 10 is a view in elevation, partly in

section, illustrating the means for moving the guide bar in and relative to the knee.

Figure 11 is a plan of the cylinder for operating the dogs to and from dogging position.

Figure 12 is a vertical sectional view of the same.

Figure 13 is an enlarged sectional detail illustrating particularly the preferred form 10 of cushioning or resilient support for the lower dog unit casting.

Figure 14 is a perspective view showing the crank mounting for the dog carrying bar.

The knee 1, aside from the specific details 15 hereinafter specifically referred to, is of conventional form with its forward portion of greatest height, the forward wall 2 of which portion constitutes the face of the knee and is provided with the usual removable wear 20 plates 3. The side walls 4 of the knee are, in the conventional form of knee, spaced apart and the face 2 is longitudinally divided to define a narrow space 5 of materially less width than the space between the side walls 25 of the knee. The space between the side walls 4 of the knee forwardly of the rear reduced portion 6 of the knee, is utilized for the reception of the dog operating mechanism of this invention, from which it will be apparent that 30 such mechanism is without overbalancing effect on the knee, and, except in the operating means for adjusting the dogs relative to the face of the knee, avoids any projection and therefore obstruction beyond the side wall of 35 the knee.

The dog operating mechanism is mounted for movement on and relative to a guide bar which extends vertically of the knee between the side walls, with said guide bar mounted 40 for selective movement toward and from the face of the knee. The means for mounting the guide bar includes upper and lower crank members each involving a crank shaft 8 adapted to be mounted in bearings 9 in the 45 knee with the inner ends of the crank shafts provided with crank arms 10 and the outer ends with right angled crank arms which include arms 11 projecting from the crank shaft in the same direction and duplicating the 50 crank arms 10 and additional arms 12 extending at right angles to the arms 11. The terminals of the arms 10 and 11 are formed as bearings to receive a crank pin 13 rigidly secured in and extending at right angles to 55 the guide bar 7 near the respective ends thereof, the crank pins, for example, having a driving fit in an opening in the guide bar and being riveted in place. Beyond the crank arm 11, the crank pins 13 are terminally threaded 60 for the reception of a nut 13' to take up play.

The arms 12 of the right angled crank arms are connected by a bar 12' to compel simultaneous movement of the cranks, one of said arms 12 being extended beyond its connection 65 with the bar 12' to provide for the connection

thereto of a piston rod 14 operating in a cylinder 15 pivotally supported on a bracket 16 projecting from one side wall of the knee. The cylinder 15 is made up of upper and lower sections 17 and 18, the latter being of 70 less diameter than the former and the sections adjacent their juncture being formed with a lower ground valve seat 19 at the lower end of the section 17 and an upper ground valve seat 20 at the upper end of the section 18.

Upper and lower pistons 21 and 22 are mounted in the respective cylinder sections with suitable packing rings to prevent leakage. The pistons are connected by a rod 23 and the upper piston is connected to the piston rod 14. The upper piston is formed at its lower end, as at 24, to cooperate with seat 19, and the lower piston 22 is formed at its upper end, as at 25, to cooperate with seat 20. 80 85

Leakage openings 26 to permit the escape of air between the pistons as the latter are operated are formed in the lower end of the upper section 17. The section 17 is formed at the upper end with an offset 27 in which 90 is formed a port 28 leading directly into the section 17 of the cylinder, the port opening slightly below the upper end of the section and in direct line with a fluid pressure pipe 29 removably connected in the offset.

The offset is further formed with a by-pass 30 communicating at one end with the port 28 and leading to and above the piston 21 when the latter is at its upper limit of movement, it being understood that such piston is held in contact with the extreme upper end of the closure for the section 17, as particularly illustrated in Figure 10. The by-pass 30 has a downwardly closing valve 31, preferably of the ball type, to prevent back pressure. 100 105

The lower end of the section 18 is formed with an offset 32 having a port 33 leading into the lower section above the lower end thereof with which a fluid pressure pipe 34 directly communicates, the offset 32 having a by-pass 35 opening into the section 18 below the extreme lower position of the piston 22, this by-pass having a valve 36 closing against return pressure. 110 115

It will be understood that, by reason of the increased area of the piston 21 as compared with the piston 22, the piston rod will move downwardly under pressure fluids of substantially the same pressure delivered 120 through pipes 29 and 34, and advantage is taken of this fact in order to save loss of pressure fluid, ordinarily air under pressure, in the operation of the device.

Thus, it will be apparent that with the air 125 under pressure maintained constantly in the pipe 34, the movement of the piston rod and thereby the adjustment of the dog carrying bar may be controlled through a single valve manipulation governing the pressure through 130 135

the pipe 29. If pressure is admitted through the pipe 29, the piston rod 14 will move downwardly notwithstanding pressure against the piston 22 owing to the differential pressure area of the pistons. When it is desired to move the piston rod upwardly, the valve controlling the pressure in pipe 29 is operated to permit exhaust of the pressure space in section 17 above the piston 21, whereupon the constant pressure below the piston 22 will move the piston rod upwardly. There is thus no loss or exhaustion of the pressure fluid below the piston 22 at any time, the loss being reduced to a minimum in that the pressure fluid above the piston 21 is the only pressure fluid exhausted to the atmosphere.

It will of course be apparent that as either piston moves to its operative position, that is, the lower position of the upper piston or the upper position of the lower piston, the respective pistons act to seal against the loss of pressure medium, the upper piston, when serving as a power piston through cooperation of its ground face 24 with the seat 19, sealing against the loss of pressure into the space between the pistons, the lower piston, when in its upper opposite position, correspondingly sealing against loss of pressure medium through cooperation of its ground face 25 with the seat 20.

Thus, the cylinder and pistons for adjusting the dog carrying bar may be operated to move the bar to either of its adjusted positions, that is, for maximum or minimum projection of the dog beyond the face of the knee, through a single valve control and with the minimum loss of motive fluid.

In order to avoid excessive wear and resultant lost motion in the parts, the crank shafts 8 and terminal arms 10, 11 and 12 are formed integrally, that is to say, as a solid forging. The bearing of the pins 13 in the terminals of the crank arms permits the necessary relative movement in the operation and any play in this movement may to a large extent be compensated for by adjustment of the terminal nut 13'.

The dogging means proper is mounted in independent units, one including the upper dog or dogs and the other including the lower dog. These units are mounted for independent sliding movement on the guide bar 7, and are adapted to be operated in their longitudinal stroke in succession through a single power means, said power means, dog mountings and connections being arranged wholly within the knee, that is, between the side walls 4 thereof.

The lower dog casting includes a cylinder 39 which is provided, in the preferred form as illustrated in Figure 1, with an offset dash-pot cylinder 40 having a bleed opening 41 about centrally of the height thereof and a duct 42 of gradually reduced depth up-

wardly leading from the duct to the upper end of the dash-pot cylinder. A piston 43 is operative in the cylinder having a piston rod 44 depending therefrom and guided in a disk 45 threaded into the lower end of the cylinder 40. As will later appear, this dash-pot serves to cushion and resiliently support the parts in operation. The cylinder 39 is formed diametrically with a radially extending plate 46, having its vertical edges formed to present rabbeted guide flanges 47, cooperating with similarly formed edges 48 of the guide bar 7. The lower dog 49, otherwise of conventional form, is secured at 50 on the plate 46, said dog extending of course forwardly of the plate. The rear end of the dog 49 is seated in an appropriately formed opening 51 formed in an enlargement 52 of the base 37.

The upper dog unit comprises a guide plate 53, the vertical edges of which are provided for an appropriate length from the upper and lower ends of the plate with guide flanges 54 and 55, formed to slidably cooperate with the described edges of the guide bar 7. That portion of the guide plate between the flanged upper and lower ends is formed on its inner edge with a laterally directed flange 56, the outer or free surface of which is in alignment with the upper and lower flanges at such inner edge of the plate. This construction provides a square abutment throughout the length of the plate for a purpose which will later appear.

The plate 53 is provided at the upper inner edge with a laterally projected ear 57 which, as evident from Figure 4, is in alignment with the circular base 37 of the lower dog unit casting. The surface of the plate 53, overlying the guide bar 7, is formed in that area provided with the guide flanges 54 and 55 with plate sections 58 and 59 of substantially identical construction. These plate sections are integral with the plate 53 and have a width at their lower ends somewhat less than that of the plate 53, and are gradually decreased in width toward their upper ends. These plate sections, except at their extreme upper ends, are in spaced parallel relation to the plate 53, and provide with that plate what may be termed a dog guiding means. The plate sections are connected to the plate 53 at their inner or rear walls, the latter extending laterally from the plate 53, and being coincident with the flange 56 to vertically extend the abutment formed by that flange.

The extreme upper ends of the plate sections 58 and 59 are of increased thickness, permitting an integral construction at this point as an additional support for the plate sections. These thickened portions provide dog limiting abutments 60. The space between the plate sections 58 and 59 and plate 53 is bridged at the lower ends of such sec-

tions by pivot pins 61 mounted at one end in reinforcements in the plate sections and at the opposite end in the plate 53, as clearly shown in Figure 3. Dogs 62 and 63 are movably supported on these pivot pins and it is to be understood in this connection that while but two such dogs are shown in the upper dog unit construction, it is contemplated that any appropriate number of dogs may be used by duplicating the formation described.

The dogs 62 and 63 are of slightly different form, so far as their portions in advance of the pivot pins are concerned, for a purpose which will be later explained. In rear of the pivot pins, however, the dogs are of bar-like form, as at 64, of a width to fit between the plate 53 and the plate sections 58 and 59 and of a length to overlie the limiting abutments 60, so as to prevent or limit movement of the dogs in one direction. The bar portions 64 of the dogs are connected by springs 65 to pins projected between the plate sections 58 and 59 and plate 53, the springs 25 acting to normally hold the dogs against the limit abutments 60, while permitting movement of the dogs in the opposite direction against the tension of the springs.

As the face plate opening 5 of the knee 30 terminates short of the upper end of the knee, in order to provide the necessary rigidity of knee structure, and as it is desired that the uppermost dog of the upper dog unit be capable of moving to a position coincident 35 with the upper end of this face plate opening, said upper dog 62 forwardly of the pivot is constructed with a portion 66 normally depending substantially in vertical line with the pivot, and with a dogging portion 67 extending forwardly of such depending portion and terminating in the usual point 68.

By this construction, the upper dog unit is permitted an increased elevation compared with that possible if the dog extended in 45 straight line with the bar portion 64. The remaining dog of this upper dog unit, as 63, preferably extends in straight line with the bar portion 64, as at 69, and is provided with an appropriate dogging point 70. Of course, 50 it is understood that the points proper may be of any desired form and may be integral or removably connected as may be found expedient.

As previously stated, the cylindrical base 55 37 of the casting of the lower dog unit receives and supports and of course seals the lower end of a cylinder 39, which extends vertically in parallel relation to the plate 53.

A piston 71 is operative in the cylinder 39 60 having a piston rod 72 which extends through a suitable packed opening in a head 73 removably secured on the cylinder 39. The piston rod 72 above the piston 71 has a diameter approximating half the diameter 65 of the upper face of the piston, thereby ma-

terially reducing the pressure area of the upper surface of the piston and constituting the respective faces of the piston of such relative areas as to provide a differential piston with respect to upper and lower pressures. 70

The cylinder 39 is formed at its upper end with an offset 74 formed with a port 75 opening into the cylinder below the upper limit of movement of the piston 71, this port having an upwardly extending by-pass 76 controlled by an upwardly opening valve 77 and leading into the upper end of the cylinder above the piston. A service pipe 78 for air under pressure is in open communication with the port 75. 75

The cylinder 39 is formed out of line with the enlargement 74 with a lateral enlargement 79 formed with a longitudinally ranging passage 80 and open at the upper end to receive an air pressure pipe 81. The lower end of the passage 80 opens at 82 into the cylinder 39 above the extreme lower position of the piston 71, the channel extending below the opening 82 and opening into the cylinder 39 at 83 below the extreme lower end 90 of the piston, the passage between the openings 82 and 83 being provided with a ball valve 84 opening in the direction of pressure from the pipe 81.

The upper end of the piston rod 72 is removably connected to the ear 57 of the upper dog unit, so that in the reciprocation of the piston, the upper dog unit is moved longitudinally of the guide bar 7. 95

As stated, the upper and lower surfaces of the piston 71 constitute a differential piston, and in the operation the air under pressure is admitted through the pipe 81 and the passage 80, past the valve 84 and through the opening 83, acting to move the piston upwardly to thereby move the dog to an inoperative or non-dogging position. During this time the air under pressure is constantly delivered through the pipe 78 and port 75 onto the upper surface of the piston, but by 100 reason of the reduced area of such upper surface, the piston will move upwardly under the pressure. In the upward movement of the piston as it passes the port 75, the air above the piston will be trapped by reason of 110 the fact that the valve 77 opens upwardly. This will form an air cushion to reduce the shock and gradually retard the upward movement of the piston. 115

When it is desired to move the dogs to an operative or dogging position, the air admitted through pipe 81 is exhausted by opening said pipe to the atmosphere, whereupon the pressure through pipe 78, which as stated is continuous, operates to force the piston 125 downwardly. The piston is cushioned at the lower end of its movement exactly in the same manner as at the upper end of such movement, as will be plain from Figure 12 of the drawings. 130

The lower dog unit casting is cushioned upon a bed plate 85 bridging the space between the side walls 4 of the knee for an appropriate length rearwardly of the face plate 2 of the knee, through the dash-pot construction previously described. A modified resilient support may be provided through a rod 86, slidably mounted in ears 87 and 88 on cylinder 39, and having a lower head 89 to bear on the bottom plate 85 of the knee. A spring 90 encircles the rod between the head and the ear 88, this spring for the greater portion of its length being housed within a skirt 91 to thereby insure direct action of the spring and prevent lateral distortion thereof in operation. The plate 85 is formed in its forward portion with a slot 92 to permit the extension of the lower dog 49 therethrough. This particular construction is shown in Figure 8 of the drawings, and it will be noted that in this instance the lower dog 49 is bolted to the plate 46 and underlies and is secured to an extension of the cylinder 39 or to a casting 93 in which the lower end of the cylinder may be positioned.

As the motor mechanism and dogs are resiliently supported, and as in operation, particularly in setting the upper dog, the parts move down with considerable force, it is apparent that in this movement the lower dog will, if rigid, move below its normal position. If the dog were rigidly connected and in the resilient movement of the motor mechanism and dogs tended to move downwardly, there would be extreme liability of the dog engaging the rack of the rack and pinion type of set works mechanism or a screw rod in the screw and block type of set works mechanism with liability of damage to the dog or to these parts of the mechanism. It is to be noted, however, that the dog, that is, the forward portion thereof, can freely yield in the upward direction and that if, in this resilient shock absorbing movement of the parts, the dog tends to contact with the rack or screw rod, the dog will yield to avoid damage to the parts. That is to say, the dog automatically accommodates itself in this movement to permit a full shock absorbing resiliency of the motor parts without liability of damage to the mechanism.

Under the shock absorbing movement of the parts as described, with the dog rigidly secured in place, damaging contact between the dog and the set works mechanism for the knee would probably occur if not provided for. To avoid this interference, it is necessary to form the rack bar 94 with a slot or channel 95 ranging from the forward end of said rack bar for a distance sufficient to accommodate the lower dog, as more particularly illustrated in Figure 7. This arrangement permits the use of a lower dog of appropriate form and size in those rigs where the set works adjust the knees through the

rack and pinion method of adjustment, without disturbing the conventional relation between the knee and rack, and therefore without in any way destroying the appropriate balance between the parts incident to the present commercial and accepted type of this particular operating means.

It will, therefore, be apparent that with the lower dog mounted for independent movement or resilient movement of the parts incident to the shock, free movement is permitted without liability of damage through contact of the dog with the set works mechanism for the knee; and that if the dog is rigidly secured against independent movement, the rack bar of such knee set works mechanism must be slotted to take care of the dog movement. The dog mounted for independent movement illustrates one form of this detail and it is apparent that such mounting to permit independent movement of the dog may be readily provided for in a variety of ways. For example, in Figure 9 a cylindrical casting or base for the reception of the lower end of cylinder 39 is indicated at 96 and is shown as provided with an enlargement 97 overlying and of course integral with plate 46 of the lower dog unit. The lower dog, here shown at 98, has the usual dog point and a shank 99 slidably mounted in a vertically extending bore 100 of the enlargement 97. The upper end of the shank 99 has a head 101 to limit the downward movement of the dog while the relation of the dog and bore in which it slides is such that the dog may yield upwardly independently of the lower dog unit to permit the full resilient shock absorbing movement of the parts without liability of damage through contact of the dog with the set works mechanism of the knee.

From the above description it will be apparent that, aside from the resilient support provided through the dash-pot or the rod 53, the entire dog mechanism and dog operating means is carried by the guide bar 7, and that the latter is movable toward and from the face of the knee through the power mechanism included in the cylinder 15, which latter is arranged beyond and at one side of the knee. In order to accommodate the guide bar and dog carrying units, and particularly to permit the necessary play of the guide bar in its adjusting movement, it may be found necessary to slightly increase the distance between the side walls 4 of the knee as compared with the conventional spacing of these walls, and if desired such walls may be laterally deflected, as indicated at 102 in Figure 5. Under these circumstances, it will be found necessary to provide additional space for the play of the lower crank 9 in order to permit the guide bar to be moved to the desired limit toward the face of the knee, and if such is required, the wall 4 adjacent the

crank will be offset, as at 103, throughout an appropriate area to permit the desired throw of the crank.

In operation, the guide bar 7 and therefore the upper and lower dog units and connected parts may be adjusted relative to the face of the knee by appropriate control of the piston within the cylinder 15, this operation simultaneously shifting the cranks 9 about 5 the crank shafts 10 as a center, and correspondingly moving the guide bar 7 bodily relative to the face of the knee. As the upper and lower dog units are carried by the guide bar, the dogs will be correspondingly projected relative to the face of the knee. This then provides for securing the desired projection of the dogs. In the normal positions of the respective dog units, the upper dog unit is at its maximum elevation, that is, the 10 piston 71 will be substantially at the upper end of the cylinder 39. Assuming it desirable to engage a log, pressure is controlled as described to force the piston 71 downwardly. This causes the upper dog unit to move downwardly on the guide bar 7 until such movement is interrupted by the appropriate dog of the upper dog unit engaging the log, cant or board, as the case may be. In this movement, it will be obvious that as the dog engages the material, movement of the dog in a direction resulting from such engagement is impossible, as the dog bears against the dog limiting abutment 60, hence for operative movement the dog may be said to be immovable. As the appropriate upper dog engages the material, movement of the piston is of course interrupted, and the continued admission of pressure to the cylinder 39 will 15 at once result in causing the cylinder to become the movable element and the piston the fixed element. Thereupon the cylinder will move upwardly, and as the cylinder is in effect a fixed part of the lower dog unit, the lower dog will, in such movement of the cylinder, be moved upwardly to engage the lower surface of the log, cant or board. With the pressure maintained, the dogs are held in gripping relation in the material and the sawing or other operation may be proceeded with.

It is to be particularly noted that, as previously described, the free or outer surface of the flange 56 and the corresponding surfaces of the plate sections 58 and 59 form an abutment to resist play of the cylinder in a direction toward the guide bar 7. It is evident that as the parts are moved to operative position, they will of necessity engage the material with considerable force, causing a sudden interruption of the movement of the parts with a consequent tendency to force the cylinder toward the guide bar. If such movement of the cylinder was permitted, a distortion of the arrangement would eventually result with loss of efficiency, and hence the 20

abutment described is provided as a substantially fixed wall to restrict any such play of the cylinder and insure a proper relative disposition of the parts under any ordinary working strains and stresses.

It will be noted that the dogs are preferably though not necessarily so constructed that at the maximum inward adjustment of the guide bar, the points of the dogs will still project to some extent beyond the face of the knee. This minimum projection has its advantages, in that when the guide bar has been adjusted to its inner position, there is still a dog projection which will serve to engage a board, whereas if the inner limit of adjustment of the guide bar was such as to withdraw the dogs wholly within the face of the knee, that disposition of the dogs necessary to engage a board would require an intermediate position of the guide bar, and thus necessitate more or less care in such adjustment which is entirely eliminated by having the inner limit of the guide bar adjustment position the dogs for board engagement. This normal projection of the dogs is without any disadvantage from the standpoint of possible damage to the dogs by being engaged by a log rolled against the knee, for it will be apparent that the dogs under such impact can readily yield against the tension of the springs 65 and thus any possible damage to the dog points is entirely avoided.

What I claim to be new is:

1. In a saw mill carriage, a knee, a guide bar relatively movable toward and from the face of the knee, a lower dog unit slidable on the guide bar, an upper dog unit slidable on the guide bar, a cylinder carried by the lower dog unit, and a piston operative within the cylinder and connected to the upper dog unit, said upper dog unit being formed to provide an abutment to limit undue play of the cylinder in one direction in the operation of the parts.

2. In a saw mill carriage, a hollow knee, upper and lower dog mechanisms mounted within said knee and including a guide bar movable toward and from the knee face, an upper dog carrying unit slidable on the guide bar, a lower dog carrying unit slidable on the guide bar, a cylinder carried by said unit, a piston operative within the cylinder and connected to the upper dog unit, and cushioning means depending from the lower dog unit and adapted to engage the base of the knee.

3. In a saw mill carriage, a knee, a guide bar movable relative to the face of the knee, a lower dog unit slidable on the guide bar, a motor mechanism carried by the lower dog unit and including a cylinder, and an upper dog unit including a plate formed with flanges to slidably embrace the guide bar, said plate on the edge next the cylinder being formed with a flange to provide a limiting

abutment for the movement of the cylinder.

4. In a saw mill carriage, a knee, a guide bar arranged within the knee and movable relatively to the face of the knee, an upper dog unit slidable on the guide bar, a dog carried by said unit, a lower dog unit including a plate formed with flanges to slidably embrace the guide bar, a motor mechanism for the respective dog units including a cylinder connected to said plate, and a lower dog carried by the plate.

5. In a saw mill carriage, a knee, rack and pinion mechanism for operating the knee, a guide bar arranged within and operative relative to the face of the knee, an upper dog unit slidable on the guide bar, a lower dog unit slidable on the guide bar, motor mechanism for operating the dog units, and a support to absorb the shock of operation of the motor mechanism on the underlying parts of the setworks, without damaging contact of the lower dog therewith in the shock absorbing movement of the parts.

6. In a saw mill carriage, a knee, a means for operating the knee, a dogging mechanism arranged in the knee including a guide bar, an upper dog slidable on the guide bar, a lower dog slidable on the guide bar, a motor mechanism for operating the dogs, and a support between the motor mechanism and knee to gradually absorb the shock of motor mechanism operation, the parts being arranged so that the damaging contact of lower dog is avoided in the play incident to the shock-absorbing function of the support.

7. In a saw mill carriage, a knee including a divided face plate, spaced side walls, and a rear wall connecting the side walls, whereby the knee provides a hollow chamber in rear of the face plate and communicating with the division in the latter, a guide bar arranged in said hollow chamber of the knee and movable toward and from the face plate, means for operating the guide bar, an upper dog slidable on the guide bar within the hollow chamber of the knee, a lower dog slidable on the guide bar within the hollow chamber of the knee, said dogs being operable through the division in the face plate in the movement of the guide bar, and a motor mechanism arranged in the hollow chamber of the knee and connected to and adapted to operate the upper and lower dogs in succession.

8. In a saw mill carriage, a knee including a face plate and spaced side walls extending rearwardly therefrom, a guide bar extending substantially parallel with the face plate and movably supported on one of said side walls and operable toward and from the face of the knee, an upper dog slidable on the guide bar, a lower dog slidable on the guide bar, and a motor mechanism for operating the dogs in succession, said motor mechanism including a cylinder arranged in substantial parallelism with and adjacent the guide bar and con-

nected to one of the dogs and a piston operating in the cylinder and connected to the other of the dogs.

9. In a saw mill carriage, a knee including a face plate and spaced side walls extending rearwardly therefrom, a guide bar extending in substantial parallelism with the face plate and movably supported on one of the side walls of the knee, motor mechanism carried by the knee beyond the side walls and operatively connected to the guide bar for the actuation of the latter, an upper dog slidable on the guide bar, a lower dog slidable on the guide bar, and fluid pressure means for operating the dogs in succession, said fluid pressure means including a cylinder arranged in substantial parallelism with an immediately adjacent the guide bar and operatively connected to one of the dogs and a piston operative in said cylinder and directly connected to the other of said dogs.

10. In a saw mill carriage, a knee including a divided face plate and side walls extending rearwardly therefrom in relatively spaced relation, a guide bar extending in substantial parallelism to the face plate and movably supported by one of the side walls, said guide bar being movable toward and from the face plate, an upper dog slidable on the guide bar, a lower dog slidable on the guide bar, and motor mechanism carried by and movable with the guide bar for operating the dogs in succession, said motor mechanism including a cylinder arranged in substantial parallelism with the guide bar and immediately adjacent thereto, said cylinder being operatively connected to one of the dogs, the piston in the cylinder operatively connected to the other of said dogs, and means to cushion the motor mechanism and thereby the dogs relative to the knee.

11. In combination with the knee of a saw mill carriage, said knee including a face plate, side walls extending rearwardly from the face plate in spaced relation, and a bed plate bridging the side walls at their lower ends, dogging mechanism arranged wholly between the side walls of the knee and above the bed plate and including a guide bar movable toward and from the face of the knee, upper and lower dogs independently slidable on the guide bar, and motor mechanism carried by and movable with the guide bar and involving relatively movable elements independently connected to the respective dogs, and means for cushioning the dogging mechanism on the bed plate of the knee, and a set works element cooperating with the knee, said element being slotted to permit non-interfering play of the lower dog in the cushioned movement of the dogging mechanism.

12. In combination, a knee for saw mill carriages including spaced hollow side walls and a divided face plate, a set works member cooperating with the knee for taper adjust-

- ment of the latter, and dogging mechanism supported wholly between the side walls of the knee and including dogs bodily adjustable toward and from the face of the knee and 5 independently movable vertically of the knee, means for cushioning the dogging mechanism to cushion its action, the set works member being longitudinally slotted in line with one of the dogs to permit the free non-interfering play of that dog in the movement of the dogging mechanism incident to its cushioned action.
13. In a saw mill carriage, a knee including a face plate, side walls extending rearwardly 15 therefrom in relatively spaced relation, a guide bar movably supported on one of the side walls and operable toward and from the face plate, an upper dog casting slidable on the guide bar, an upper dog pivotally supported on said casting, a lower dog casting slidable on the guide bar, a lower dog carried by said lower dog casting, a cylinder directly supported by the lower dog casting and extending immediately adjacent and in 20 substantial parallelism to the guide bar, a piston operative within the cylinder and directly connected to the upper dog casting, and means for admitting fluid pressure to the cylinder.
14. In a saw mill carriage, a knee including a face plate, side walls extending rearwardly 25 therefrom in relatively spaced relation, a guide bar movably supported on one of the side walls and operable toward and from the face plate, a guide plate overlying and bearing against one surface of the guide bar and connected to the guide bar for sliding cooperation therewith, independent dogs pivotally supported on said guide plate, a lower dog 30 casting slidable on the guide bar, a dog carried by the lower dog casting, a cylinder supported in said casting and extending in substantial parallelism to the guide bar and adjacent thereto, and a piston operative within 35 the cylinder and connected to the guide plate above the dogs carried thereby.
15. In a saw mill carriage, a knee including a face plate, side walls extending rearwardly 40 therefrom in relatively spaced relation, a guide bar movably supported on one of the side walls and operable toward and from the face plate, a guide plate overlying and bearing against one surface of the guide bar and connected to the guide bar for sliding cooperation therewith, independent dogs pivotally supported on said guide plate, means carried by the guide plate for pivotal movements of the dogs in one direction, a lower dog casting slidable on the guide bar, a dog 45 carried by the lower dog casting, a cylinder supported by said casting and extending in substantial parallelism to the guide bar and adjacent thereto, and a piston operative within 50 the cylinder and connected to the guide plate above the dogs carried thereby.
16. In a saw mill carriage, a knee, a guide bar movable relative to the face of the knee, upper and lower dog units mounted on the bar, means for supporting the bar for movement toward and from the face of the knee, 55 said means including a crank shaft having bearing in the knee, radial arms at the respective ends of the shaft, and a crank pin anchored in the guide bar and bearing in the free ends of the arms, said crank shaft and radial arms being formed as an integral member, means connecting similar crank arms to compel unit movement, and fluid pressure means connected to one of the crank arms for 60 operating the same.
17. In a saw mill carriage, a knee, a guide bar movable relative to the face of the knee, upper and lower dog units mounted on the bar, means for supporting the bar for movement toward and from the face of the knee, 65 said means including crank shafts having bearing in the knee, inner crank arms projecting from the shafts, outer crank arms of right angled form projecting from the shafts, crank pins anchored in the bar and having bearing in the similar crank arms at the respective ends of the shafts, said crank shaft and crank arms being formed as an integral 70 unit, and means for operating the crank arms simultaneously.
18. In a saw mill carriage, a knee, a guide bar movable relative to the face of the knee, upper and lower dog units mounted on the bar, means for supporting the bar for movement toward and from the face of the knee, 75 said means including crank shafts having bearing in the knee, inner crank arms projecting from the shafts, outer crank arms of right angled form projecting from the shafts, one of the crank pins being anchored in the bar and having bearing in the similar crank arms at the respective ends of the shafts, said crank shaft and crank arms being formed as an integral unit, terminal nuts for the anchored crank pins to compensate for wear in the connection, and means for operating the 80 crank arms simultaneously.
19. In a saw mill carriage, a knee, a guide bar movable relative to the face of the knee, upper and lower dog units mounted on the bar, means for supporting the bar for movement toward and from the face of the knee, and a motor mechanism for operating said means, said motor mechanism including a differential cylinder, differential pistons operative in the cylinder, a piston rod intermediate said pistons and said means, and a motive fluid under pressure for controlling the movement of the pistons, said pistons acting as seals in their limit positions.
20. The combination with a knee, of a guide member thereon, a dog carrier vertically movable with respect to the guide member, a plurality of dogs pivotally mounted on the dog carrier, abutments on the dog carrier to 85

limit the movement of the dogs on their pivots in a direction to maintain the points of the dogs in operative position, and means whereby the dogs may be influenced to contact with said abutments, said dogs being freely movable in a direction away from said abutments to permit the operative ends of the dogs to move under knee impact to avoid breakage of the dogs.

10 In testimony whereof I affix my signature.
GEORGE M. PELTON.
